UNITED STATES PATENT OFFICE.

FRANK SIMONYE, OF NEW YORK, N. Y.

WASHING MACHINE.

Application filed September 10, 1921. Serial No. 499,800.

To all whom it may concern:

Be it known that I, FRANK SIMONYE, citizen of Yugoslavia, residing at New York, in the county of New York and State of New York, have invented certain new and useful Improvements in Washing Machines, of which the following is a specification.

This invention relates to clothes washing machines, having for a general object to provide a simple and inexpensive machine of this sort.

A further object of the invention is to provide a clothes washing machine which may be mounted as an attachment on wash-tubs such as are commonly provided in dwellings.

For further comprehension of the invention, and of the objects and advantages thereof, reference will be had to the following description and accompanying drawings; and to the appended claims in which the various novel features of the invention are more particularly set forth.

Figure 1 of the drawings is a plan view of a clothes washing machine, showing it mounted on a wash-tub.

Figure 2 is a side elevation thereof.

Figure 3 is a side elevation, looking in the opposite direction to Figure 2, part of the tub and the attaching clamp being broken away.

Figure 4 is an end view, the machine being tilted back, showing the parts as they appear in underside plan view when the machine is in operative position.

Figure 5 is a side view of one of the bearing boxes.

Figure 6 is an edge view thereof.

Figure 7 is a fragmentary longitudinal vertical section.

As here shown my improved clothes washing machine comprises a pair of side frame plates 10 which are provided with rearwardly extending lugs 11 in which are fixed laterally projecting pins 12 which engage in bearing brackets 13 adapted to rest upon the top side edges of a wash-tub 14 of ordinary construction. The brackets 13 have their lower edges channeled to receive the usual bead 14' extending around the top of the tub 14 and are adapted to be secured to the latter by set-screws 15 threaded laterally through the brackets. The brackets 13 have also set-screws 16 threaded vertically there-through and adapted to engage the pins 12.

Extending forwardly from the side plates 10 are a pair of bearing rails 20 in which are

journalized a series of shafts 21 upon which are fixed the closely spaced feed rollers 22 which are adapted to feed the clothes between a pair of rotary cylindrical brushes 24, 25 arranged one above the other. These brushes 24 and 25 are suitably fixed on shafts 26 and 27 supported in the side plates 10. Located adjacent the brush 25 is a delivery roller 28 which is fixed on a shaft 29 journaled in the side plates 10. Adjacent this delivery roller 28 is a short delivery chute 30 which is secured to the side plates 10. These rollers 22 and brushes 24, 25 are driven as follows:

Fixed on the roller shafts 21 and 29 are sprocket wheels 35 over which is looped a sprocket chain 36, engagement of the chain with the intermediate sprocket wheels being ensured by means of suitably supported idler rollers 37 which bear on the top thereof. Fixed to the shaft 22 of the roller 21 which is nearest the brushes, is a gear 38 which meshes with a gear 39 fixed to the trunnion of a roller 41 located above, and co-operating with the inner one of the rollers 22. Gear 39 is driven, through a pair of idlers 40 and 41, from a gear pinion 42 fixed on a stub shaft 43 mounted in one of the side plates 10, in which the idlers 39, 40, 41 are also supported. The stub shaft 43 may have a crank handle 44 fixed thereon for manual rotation or the machine may be power operated if desired. To drive the brushes 24, 25 the shafts 26 and 27 have gears 49 and 50 fixed thereon, the former meshing with a gear 51 fixed on the stub shaft 43. To enable the brushes 24, 25 to be readily removed or replaced their carrying shafts 26, 27 are supported at one end by a removable plate 52 set into one of the side plates 10 and secured by screws 53. The relative sizes of the driving gears for the brushes 24, 25 and the rollers 22 is such as to give the brushes a faster surface speed than the rollers.

The clothes to be washed may be placed on a table 55 having notches 56 cut in the inner corners thereof to receive the ends of the rails 20 to which latter it is connected by screws 57 and 58, the latter of these screws being provided with wring-heads so that they may be readily withdrawn from engagement with the table if desired, to enable the latter to be swung downward, as indicated in dot and dash lines in Figure 3.

The clothes entering between the brushes 24 and 25 have water discharged thereon

from a perforated pipe 60 extending across the machine, this pipe leading from a pump 61 supported by and under an inward projection 62 on one of the side plates 10, this 5 pump having an intake pipe 63 extending down and into the tub 14 in which a supply of water is placed. The pump 61 is driven by a sprocket chain 64 looped over a sprocket wheel 65 on the rotor of the 10 pump, an idler 67 and over a sprocket wheel 66 fixed to shaft 26.

The brush 25 and adjacent one of the rollers 22 are preferably mounted on resilient supports such as are shown in Figures 15 5 and 6. The supports comprise the open frames 70 having slotted sides 71 in which are guided the bearing blocks 72. These blocks rest on springs such as 73 interposed therebetween and the lower horizontal members 20 of the frames 70, screws such as 74, being threaded downward through the top members of the frames 70 to adjustably position the blocks 72.

In the use of my improved machine the 25 latter is placed on the tub 14 and the screws 15 tightened, after a quantity of suitably treated water is placed in the tub. The clothes are placed on the table 55 and fed by hand onto the first of the rollers 22 which 30 feed them forward to the brushes 24, 25 between which they pass, falling down the chute 30 into the tub 14, from which they may be removed and the operation repeated as often as may be necessary.

It will be noted that, by reason of the 35 greater surface speed of the brushes 24, 25 over the rollers 22, 41, the brushes have a rubbing action on the clothes, the respective springs 73 supporting the brush 25 and roller 22 being of such relative strength as to give 40 a greater frictional grip or bite of the rollers 41' and 22 on the clothes than that of the brushes 24 and 25.

Having thus described my invention what I claim as new and desire to protect by 45 Letters Patent of the United States is as follows:

1. In a clothes washing machine, a pair of rotary brushes, a series of rollers adapted to feed the clothes between said brushes, 50 a pair of brackets adapted to be fixed upon a wash-tub, a frame supporting said rollers and brushes, and means pivoting said frame to said brackets.

2. A clothes washing machine comprising 55 a pair of side frames, a pair of brushes and a series of feed rollers supported by said frames, a table arranged in front of said rollers, a perforated pipe extending across the machine in front of said brushes, a 60 pump supported by one of said side frames and having the said pipe connected thereto, and means for driving said brushes, rollers and pump.

In testimony whereof I have affixed my 65 signature.

FRANK SIMONYE.
